MEANS FOR CHECKING THE OPERATION OF A TRACK INSTRUMENT

Ralph R. Kemmerer, Swissvale, Pa., assignor to Westinghouse Air Brake Company, Wilmerding, Pa., a corporation of Pennsylvania

Application December 21, 1953, Serial No. 399,201

13 Claims. (Cl. 246—160)

My invention relates to means for checking the operation of a track instrument.

Track instruments are often used along the wayside of a stretch of railway track in order to detect the presence of trains and vehicles moving through the stretch. Such track instruments may take many forms, such as microphones, photoelectric units or treadle actuated rail contactors such as that shown and described in Letters Patent of the United States No. 2,588,798, issued March 11, 1952, to Herbert L. Bone and Kenneth J. J. McGowan, for Buffer Means. Track instruments are usually employed in place of track circuits where it is inconvenient or uneconomical to utilize track circuits for the particular application. Ordinarily, in track instruments, a contact is operated when a train comes into engagement with or in close proximity to the track instrument and when the train moves out of engagement with or out of close proximity to the track instrument, the instrument contact will be restored to its normal condition. Therefore, if it is desired to provide a continuous indication of the presence of a train in a stretch of track even though the train may not be close to nor in engagement with the track instrument at the particular time, some additional apparatus is necessary.

One example of an application in which a track instrument may replace a track circuit is in a switch locking arrangement. Ordinarily, when a hand-throw switch is employed, a switch lock is employed for preventing the switch from being thrown to its reverse position while a train is approaching the switch. However, if it is desired to move a train approaching the switch along the main line into a siding, thereby necessitating a reversal of the switch, there must be means provided for unlocking the switch. In the past this has been accomplished by utilizing a short track circuit immediately in approach to the switch, which when occupied, would place the switch in a condition to become unlocked, thereby conditioning the switch for a reversal of position. Such a function can be performed by employing a track instrument.

One object of my invention is to provide means for checking the operation of a track instrument.

Another object of my invention is to provide means for checking the operation of a track instrument so that a continuous indication of the presence of a train or vehicle in a particular portion of a stretch of railway track will result.

It is a further object of my invention to provide, in means for checking the operation of a track instrument, means for preventing the operation of the track instrument checking means if the track instrument contacts become inoperative in their actuated positions.

According to a preferred form of my invention in which the instrument whose operation is to be checked is used to control the unlocking of an electrically locked switch, the instrument is located in approach to the switch in such a position that it will be actuated by each train approaching the switch in a facing point di-

rection when the train has moved to within a predetermined distance from the switch. The stretch of track in which the switch is located is provided with the usual track circuit, and associated with the instrument are two control relays. The first control relay is provided with an energizing circuit which becomes closed only when the track section is occupied, the track instrument occupies its normal position and the second control relay is deenergized, and with a stick circuit which becomes closed as soon as the first control relay becomes energized. The second control relay is provided with a pick-up circuit which becomes closed only when the track section is occupied and the track instrument is actuated by a train, and a stick circuit which becomes closed when the second relay picks up provided the first relay is then energized. The lock can only be energized when both relays are picked up. It follows, therefore, if the track instrument is not operating properly so that it is blocked in its actuated condition, or its contacts are bridging, when a train approaching the switch enters the section, the second relay will become energized to prevent the first relay from becoming energized. Accordingly, the switch lock cannot be energized to unlock the switch when a train approaches the switch in a facing point direction and the track instrument is functioning improperly.

Other objects of my invention will become clear hereinafter as the characteristic features of construction and mode of operation of my novel means for checking the operation of track instruments is described in detail.

I shall confine my description to a switch locking arrangement where a track instrument of the treadle actuated type is employed to effect an unlock. It will be understood that my invention is not limited to this particular application nor to this particular type of track instrument but may be used whenever the operation of any type of track instrument must be checked.

The single accompanying drawing is a diagrammatic view of apparatus for the control of a railway switch employing a track instrument for effecting an unlock of the switch and means for checking the operation of that track instrument embodying my invention.

Referring now to the drawing, a stretch of railway track made up of the track rails 1 and 2 is provided with an insulated track section LT by the inclusion of insulated joints 3 in the rails. A switch W connects the section with a siding S made up of rails 6 and 7. A portion of the siding S sufficiently long to extend beyond the fouling point of the switch is preferably insulated from the remainder of the siding by insulated joints 3, and this insulated portion of the siding is connected with the rails in section LT by a jumper 4 and the frog arrangement at the switch.

Associated with section LT is a track circuit including a source of energy, here shown as a track battery LTB, and a track relay LTR having a normally open back or control contact *a*. It will be obvious that other sources of track circuit energy may be employed.

A track instrument WLZ is located within the section LT a short distance from the switch so that whenever a train approaches the switch in a facing point direction, that is, from the left as viewed in the drawing, the track instrument will be actuated by the train. The distance between the instrument and the switch may vary but it is preferably approximately fifty feet. The track instrument WLZ, as here shown, is provided with a normally closed contact *a* which becomes open, and a normally open contact *b* which becomes closed whenever the instrument is actuated by a train or vehicle.

The track instrument WLZ and the track relay LTR control a first control or stick relay WLZNPR and a second control or stick relay WLZSPR. Relays WLZNPR

and WLZSPR in connection with a manually operated contact, here shown as a push button contact PB, control a switch lock WL operatively connected with a switch lever K for manually operating the switch W.

The switch lock WL may be of any of the well-known types and is illustrated conventionally in the drawing. For purposes of my present invention, it is sufficient to point out that when the switch lock WL is deenergized and switch W is in its normal position, pawl P will fall into a notch in a lever quadrant Q forming part of the switch lock WL to prevent switch lever K from moving the switch W out of its normal position. However, when switch lock WL is energized, pawl P will be lifted out of the notch in its lever quadrant Q to permit free motion of lever K and switch W. It will also be obvious that, when the switch W is in its reverse position, lever K can be freely moved back to its normal position to restore switch W to its normal position regardless of the condition of switch lock WL. As shown, push button contact PB is open. In actual practice, the push button contact PB would preferably be a contact associated with a normally locked door on the switch lock WL. When such an arrangement is used, a trainman desiring to operate switch W will unlock and open the door, thereby closing push button contact PB. In order to restore the door operated contact to its normally open position, the trainman must close and lock the door. Such an arrangement will prevent unauthorized persons from reversing the switch W. Actually, the inclusion of push button contact PB is not necessary to the operation of my track instrument checking means but it is desirable in the embodiment shown for reducing drain on battery LB by making switch lock WL normally deenergized, and it is necessary from a safety standpoint in such an embodiment to keep switch W locked at all times except when authorized personnel desire to unlock the switch W.

The energy for operating the relays WLZNPR and WLZSPR and switch lock WL, as here shown, is supplied by a battery LB having a positive terminal B and a negative terminal N.

The apparatus is shown in its normal condition with the stretch of track unoccupied and switch W in its normal position, thereby permitting traffic to move along the stretch but not into or out of siding S. With the stretch unoccupied, track relay LTR is energized and no energy is being supplied to relays WLZSPR and WLZNPR. Therefore, these latter relays are released. Furthermore, push button contact PB is open so that no energy is supplied to switch lock WL and, accordingly, pawl P is in the notch of lever quadrant Q, thereby locking the switch W in its normal position.

I will now assume that a train or vehicle moving along the siding S from right to left desires to enter the main track. Under these conditions, the train will stop in approach to the fouling point of the switch and the trainman will operate the push button contact PB associated with switch lock WL. This will complete a circuit passing from the positive terminal B of battery LB, over the push button contact PB, front contact b of relay LTR and the winding of switch lock WL to negative terminal N of battery LB. Accordingly, switch lock WL will become energized and pawl P will be lifted out of the notch in lever quadrant Q to thereby unlock switch W and permit the trainman to reverse the switch. As soon as the trainman has reversed switch W, the train may move out onto the main stretch of track. Track relay LTR will release as soon as the train passes the fouling point, and the releasing of relay LTR will open the energizing circuit for switch lock WL. Push button contact PB may now be allowed to return to its normally open position. With switch lock WL deenergized, pawl P will drop onto the periphery of lever quadrant Q but since the switch is in its reverse position pawl P cannot drop into the notch to lock switch W. Accordingly,

switch W will be free to be restored to its normal position by operating lever K to its normal position, and the trainman will do this as soon as the rear end of the train clears the switch W, whereupon pawl P will again drop into the notch of lever quadrant Q to relock the switch W in its normal position.

It will be obvious that if a train is occupying section LT when the trainman attempts to reverse the switch W, the reversal will not be accomplished since track relay LTR will be released, thereby opening the previously traced energizing circuit for switch lock WL and causing the switch W to remain locked. It will be seen, therefore, that a train cannot move out of siding S onto the main stretch of track while section LT is occupied.

I will now assume that a train enters section LT from the left and that it is desired to move the train out of the main stretch of track onto siding S at switch W. Upon the train entering section LT, relay LTR will release and will thereby close an energizing circuit for relay WLZNPR passing from positive terminal B of battery LB, over back contact a of relay LTR, front contact a of track instrument WLZ, back contact a of relay WLZSPR and the winding of relay WLZNPR to negative terminal N of battery LB. Accordingly, relay WLZNPR which is a slow pickup relay will pick up after a short interval of time, and will establish a stick circuit including back contact a of relay LTR and front contact a of relay WLZNPR. This stick circuit will cause relay WLZNPR to remain energized so long as section LT continues to be occupied by the train. When the train actuates track instrument WLZ, it will open its front contact a and close its back contact b. With normally open contact b now closed, a circuit will be established for energizing relay WLZSPR passing from positive terminal B of battery LB, over back contact a of relay LTR, back contact b of track instrument WLZ and the winding of relay WLZSPR to negative terminal N of battery LB. With relay WLZSPR picked up, a stick circuit passing from positive terminal B of battery LB, over back contact a of relay LTR, front contact b of relay WLZSPR, front contact b of relay WLZNPR and the winding of relay WLZSPR to negative terminal N of battery LB will become established, and relay WLZSPR will therefore remain energized so long as the train occupies section LTR. It will be seen that once the track instrument WLZ has been initially actuated, there will be no effect on the condition of the apparatus when the track instrument contacts are restored to their normal condition after the first set of wheels moves out of engagement with track instrument WLZ and then are recurrently operated as other wheels actuate track instrument WLZ since the stick circuits supplying energy to relays WLZNPR and WLZSPR are not controlled by the track instrument contacts. It will also be obvious that track instrument WLZ may be made sufficiently slow acting to remain in its actuated condition rather than moving between its actuated and normal conditions each time the wheels of a train move into and out of engagement with the track instrument WLZ. This will, however, have no effect upon the operation of the apparatus as already described.

When the train reaches switch W, a trainman will close the push button contact PB. Accordingly, a second energizing circuit for switch lock WL will be established passing from positive terminal B of battery LB, over push button contact PB, front contact c of relay WLZNPR, front contact c of relay WLZSPR and the winding of switch lock WL to negative terminal N of battery LB. Accordingly, pawl P will be picked up out of the notch in lever quadrant Q and the switch may be moved to its reverse position. With the switch now in its reverse position, the train may move onto the siding S. After the train has cleared switch W, the trainman will restore the switch W to its normal position in which

lever quadrant Q will be moved to the position in which pawl P is aligned with the notch in the quadrant Q, and as a result the pawl P will drop into the notch as soon as the trainman opens the push button contact PB. This will normally be accomplished automatically by restoring the door on the switch lock WL to its normally closed condition. When the train vacates section LT, relay LTR will pick up, thereby deenergizing relays WLZNPR and WLZSPR and restoring the arrangement to its normal condition.

A desirable feature of my invention is achieved by the requirement that relays WLZNPR and WLZSPR must operate in proper sequence in order to unlock switch W. Because of this requirement false operation of the apparatus will be prevented in the event that track instrument WLZ becomes blocked in its operated position with normally open contact *b* closed and normally closed contact *a* open. If this is the case, when a train enters section LT and relay LTR releases to thereby close the previously traced energizing circuit for relay WLZSPR, relay WLZSPR will pick up and prevent the subsequent closing of the energizing circuit for relay WLZNPR including back contact *a* of relay WLZSPR. With the energizing circuit for relay WLZNPR open, it will be obvious that the second traced energizing circuit for switch lock WL cannot be closed and, accordingly, switch W cannot be unlocked. This will give a positive indication to the trainman who is attempting to throw the switch that there is something faulty in the apparatus and therefore will assure prompt repair.

In the event that track instrument WLZ became blocked in a position in which its contacts were bridging, that is, both contacts *a* and *b* were closed, upon a train entering section LT, relay LTR would release and thereby energize both relays WLZSPR and WLZNPR over their previously traced energizing circuits. However, with relay WLZNPR provided with a slow pickup characteristic, relay WLZSPR will pick up prior to relay WLZNPR and thereby open the energizing circuit for relay WLZNPR at back contact *a* of relay WLZSPR. Accordingly, relay WLZNPR will not become energized and, therefore, switch lock WL will not become unlocked. It is therefore assured by my novel arrangement that switch W can only be unlocked when the apparatus is operating in a proper manner.

Although I have herein shown and described only one form of my novel means for checking the operation of a track instrument, it will be understood that various changes and modifications may be made therein within the scope of the appended claims without departing from the spirit and scope of my invention.

Having thus described my invention, what I claim is:

1. In combination with a stretch of railway track provided with a track section, a track instrument in said track section, first and second relays; traffic responsive means operatively connected to said track section and actuated to a first position when said section is occupied and to a second position when said section is unoccupied, circuit means closed when said traffic responsive means is in its first position, said second relay is deenergized and said track instrument occupies its normal position for energizing said first relay; circuit means for maintaining said first relay energized as long as said section remains occupied, circuit means for energizing said second relay when said section is occupied and said track instrument is actuated, circuit means for maintaining said second relay energized as long as said section remains occupied, and control means controlled by said first and second relays.

2. In combination with a stretch of railway track provided with a track section, a track instrument in said section, a first relay provided with a slow pickup characteristic, a second relay; circuit means closed by a train occupying said track section, said second relay in its

deenergized condition and said track instrument in its normal position for energizing said first relay; circuit means for maintaining said first relay energized as long as said section remains occupied, circuit means for energizing said second relay when said section is occupied and said track instrument is actuated, circuit means for maintaining said second relay energized as long as said section remains occupied, and control means controlled by said first and second relays.

10 3. In combination with a stretch of track provided with a track section, said track section being provided with a track circuit including a track relay, a track instrument in said section, a first relay provided with a slow pickup characteristic, a second relay; means effective when said track relay is deenergized, said track instrument occupies its normal position and said second relay is deenergized for energizing said first relay; a stick circuit for said first relay closed when said track relay is deenergized, means effective when said track relay is deenergized and said track instrument is actuated for energizing said second relay, a stick circuit for said second relay closed when said track relay is deenergized, a control device, a first means effective only when said track relay is energized for energizing said control device, and a second means effective only when said first and second relays are energized for energizing said control device.

15 4. In combination with a stretch of railway track provided with a track section, a switch and a track instrument in said section, said switch and track instrument being so located in said section that a train approaching said switch in a facing point direction will actuate said track instrument before reaching the switch, a first slow pickup relay, a second relay; circuit means closed by a train occupying said section, said track instrument in its normal position and said second relay in its deenergized condition for energizing said first relay; stick circuit means effective as long as said section remains occupied for maintaining said first relay energized, circuit means for energizing said second relay when said section is occupied and said track instrument is actuated, circuit means for maintaining said second relay energized as long as said section remains occupied, a switch lock for preventing said switch from being reversed when said switch lock is deenergized, circuit means for energizing said switch lock when said section is unoccupied, and circuit means for energizing said switch lock when said first and second relays are energized.

20 5. In combination with a stretch of track provided with a track section, a traffic responsive element having a control contact associated with said track section, a track instrument in said section, a first relay provided with a slow pickup characteristic, a second relay; means controlled by said control contact, said track instrument and said second relay for energizing said first relay, a stick circuit for said first relay controlled by said control contact, means controlled by said control contact and said track instrument for energizing said second relay, a stick circuit for said second relay controlled by said control contact and said first relay, and control means controlled by said first and second relays.

25 6. In combination with a stretch of track provided with a track section, said track section being provided with a track circuit including a track relay, a track instrument located in said section, a first relay provided with a slow pickup characteristic, a second relay; means controlled by said track relay, said track instrument and said second relay for energizing said first relay; a stick circuit for said first relay controlled by said track relay; means controlled by said track relay and said track instrument for energizing said second relay, a stick circuit for said second relay controlled by said track relay and said first relay, and control means controlled by said first and second relays.

30 7. In combination with a stretch of track provided

each of said first and second relays for energizing said switch lock.

10. Apparatus of the class described, comprising, in combination; a stretch of track, a track relay energized through the track rails of said stretch and deenergized by a train shunting said rails, said track relay having a contact closed in the deenergized condition; a track instrument located along said stretch and having a contact closed in response to the passage of a train along said stretch; a control relay; an energizing circuit for said control relay comprising said contacts in series; a contact of said control relay closed in its energized condition; a switch lock; a manually operated contact associated with said switch lock; and an energizing circuit for said switch lock comprising said control relay contact and said manually operated contact in series.

11. Means for checking the operation of a track instrument located on a stretch of track, comprising, in combination, a track relay responsive to the occupied or unoccupied condition of said stretch, a control relay, an energizing circuit for said control relay controlled by said track instrument and said track relay, a stick circuit for said control relay controlled by said track relay, a switch lock, a manual contact associated with said switch lock, and energizing circuit means for said switch lock comprising said manual contact and a contact of said control relay.

12. In combination with a stretch of track provided with a track section, said track section being provided with a track circuit including a track relay, a track instrument located in said section and having a first normally closed contact and a second normally open contact, a first relay provided with a slow pickup characteristic, a second relay; means including a back contact of said track relay, said first contact and a back contact of said second relay for energizing said first relay; a stick circuit for said first relay including a back contact of said track relay, means including a back contact of said track relay and said second contact for energizing said second relay, a stick circuit for said second relay including a back contact of said track relay and a front contact of said first relay, and control means including a front contact of each of said first and second relays.

13. Apparatus for controlling a railway switch lock connected with a railway switch associated with a section of railway track, a track relay responsive to traffic conditions in said section, a control relay, a track instrument located in said section in approach to said switch, an energizing circuit for said control relay controlled by said track instrument and said track relay, a stick circuit for said control relay controlled by said track relay, a manually operable contact for said switch lock, and a control circuit for said switch lock including said manually operable contact and a contact of said control relay.
